UNITED STATES PATENT OFFICE.

OSCAR C. RIXSON, OF NEW ROCHELLE, NEW YORK.

CASEMENT-OPERATOR.

1,179,963.

Specification of Letters Patent. Patented Apr. 18, 1916.

Original application filed November 19, 1914, Serial No. 872,877. Divided and this application filed September 30, 1915. Serial No. 53,360.

To all whom it may concern:

Be it known that I, OSCAR C. RIXSON, a citizen of the United States, residing at New Rochelle, in the county of Westchester and 5 State of New York, have invented certain new and useful Improvements in Casement-Operators, of which the following is a full, clear, and exact description.

This invention relates to casement operators. In my former application Serial No. 872,877, filed November 19, 1914, I have disclosed an operating mechanism which is adapted to actuate swinging closures of various kinds, such as casements, transoms and 15 the like, and in that application I have shown as illustrative of the invention a form of casement operator which disclosed novel features of construction other than the parts of the operating mechanism which are germane to all classes of swinging closures.

This case is a division of my former application and is confined to the casement operator.

One of the objects of this invention is to 25 provide a casement operator which, without requiring any change in the construction of the parts, may be readily installed within the window frame so that it is concealed from view or may be mounted in exposed 30 position upon the window frame.

Another object of my invention is to provide an operator in which the lever arm which is slidably connected to the sash of the window is of a minimum length when 35 the window is in its closed position whereby, should the window become stuck, the lever arm will be less liable to be injured when the necessary power is applied to the same to open the casement.

40 A further object of the invention is to provide a casement operator in which the entire actuating mechanism for the swinging arm is concealed within a relatively small casing so that when the operator is mounted in exposed position, it will present a neat and sightly appearance.

With these and other objects in view, my invention consists of the combinations and constructions of parts which will be hereinafter described and particularly set forth in the appended claims.

In the accompanying drawings: Figure 1 is a plan view of a portion of a casement and its frame having associated therewith a concealed casement operator embodying the

principles of my invention, the stool of the window frame being removed to more clearly show the parts; Fig. 2 is a vertical section of Fig. 1; Fig. 3 is an enlarged view of the operator and the anchor piece which connects it to the sash; and Fig. 4 is a section through the swinging arm and the anchor piece.

In the form illustrated, the casement operator is of the concealed type; that is, the parts are so arranged that when the casement is closed they are hidden from view. The casement or window frame is of a common construction and comprises a sill 1 to which is secured an apron or trim 2, and a stool 3. The stool 3 is preferably spaced from the sill 1 by means of a block 4 which leaves a recess or chamber *a* which is adapted to receive the casement operator which will be hereinafter described. If desired, instead of spacing the stool 3 by means of a block 4, the space or recess *a* may be formed by mortising the sill and stool, since the chamber required for the device is small. The hinged window or casement 5 is mounted upon the side board 7 of the window frame by means of hinges 6. A weather strip 8 may be secured to the strip 7 in order to prevent the passage of air between the casement sash 5 and the board 7, the construction described being such that the casement swings outwardly as is the usual practice.

Secured to the inner face of the bottom strip of the casement sash is a plate 9 carrying an offset finger 10. This member which will hereinafter be referred to as the anchor piece is preferably inset into the sash as shown. In the concealed type of casement operator the finger on the anchor 95 piece projects into the recess or chamber *a* when the casement is closed and the bottom edge of the plate 9 is flush with the bottom of the window sash.

Mounted within the chamber or recess *a* 100 is a casing which comprises a flat base plate 12 which is secured to the sill 1 of the window by screws 13. Pivotedly mounted upon a stud 15 carried by the base plate is a swinging arm 14 comprising a solid portion 14' over the outer end of which is fitted a hollow tubular bar or member 16. The member 16 is slotted in its under face as at 17 and has its outer end closed by a cap 18. The anchor piece 10 which extends beneath 110

the swinging arm carries a pin 19 at its outer end which projects into the hollow member through the slot 17. Pivotally mounted upon the pin and positioned within the hollow member is a sliding block 20 which may be of fiber or other suitable material so that when power is applied to the arm to swing it upon its pivot, the block will slide within the member 16 to move the casement to its open or closed position.

The actuating mechanism for the swinging arm is mounted within a casing or box like housing 21, the bottom of which is formed by the base plate. The swinging arm is extended beyond its pivotal point as at 22 and projects into the casing through a suitable slot in its side wall adjacent the swinging arm. This side wall is shaped somewhat irregular to permit the swinging arm to move to its fully open position without interference. Mounted within the casing is a screw or threaded shaft 23, one end of which is of reduced diameter and has a bearing in a plug 24 which is threaded into a suitably shaped aperture or opening in one of the other side walls of the casing; the other end of the threaded shaft which is also of reduced diameter passes through a bearing in a boss 25 projecting laterally from the opposite side wall of the casing. Steel washers 26 and 27 are preferably provided at each end of the threaded portion of the shaft to take up the wear occasioned from the end thrust and also serve to prevent it from having any free play. Mounted upon the shaft or screw 23 is a traveling nut 28 which has projecting from it a lug 29. Pivoted links 30 connect the extension 22 of the swinging arm with the lug 29 so that as the nut travels along the screw, its motion will be communicated to the hollow swinging arm to angularly move the same and cause the block 20 to ride within the same and thereby open or close the casement.

As will be clear from Fig. 1, the end of the threaded shaft which passes through the boss is squared and extends through the apron or trim 2 of the window frame. This squared end receives a crank 31 through which power is applied to the threaded shaft. It will therefore be seen that all of the actuating mechanism with the exception of the exposed squared end which receives the crank is concealed within the casing or housing 21. When the casement operator is mounted in exposed position upon the stool of the window frame, none of the actuating parts are therefore in sight and the device presents a slightly and attractive appearance. This is especially true where the casing and swinging arm are plated with silver or other metals to add to their ornamental appearance. It is also of advantage to utilize a tubular arm and emplace within this arm the sliding

block carried by the anchor piece, for by this construction the outside finished surface of the arm and the anchor piece are not in sliding contact with each other and there is no danger they will be scratched or otherwise mutilated when the casement is opened or closed.

The fact that the slot 17 is in the bottom face of the hollow swinging arm whereby the slot and the connections between the swinging arm and anchor piece are concealed from view also adds to the appearance of the operator. Numerous advantages arise if this connection described is used rather than the old connection which consists of a swinging arm having a part at its extreme end which rides in a grooved slide-way carried by the sash of the window. One advantage is that it permits the same operator to be readily installed either in concealed or exposed position since the anchor piece may be positioned upon the face of the sash at any distance from the bottom of the window. For example, when the operator is mounted in exposed position upon the stool of the window frame, the anchor may be placed at a sufficient distance above the bottom of the sash of the window to insure the proper co-operation of the parts or it may be mounted flush with the bottom of the sash when the operator is concealed beneath the stool of the window frame. Another advantage resulting from utilizing an anchor piece is that when the casement is in its closed position, the length of the swinging arm; that is, the distance between its pivotal point determined by the hinges 6 and the point at which the arm is engaged by the anchor piece, is shorter than it is in any other position of the window. It is only when the casement is in its closed position and becomes stuck that considerable power is required to open the casement. The arm will therefore resist bending to a greater extent than the longer arm which is necessary in the old constructions. A still further advantage is that the distance between the hinge which connects the casement to the window frame and the point at which the swinging arm engages the window does not vary in the different positions of the window. This is important since in the old construction, the point of engagement of the swinging arm slides along the window sash and approaches the hinge as the window is opened and when the window occupies its fully opened position, these two points are relatively close. In such constructions, a heavy wind has frequently caused the hinges to give way, since the casement sash under these conditions acts as a lever upon the hinge with a fulcrum point at the point at which the swinging arm engages the window sash which is immovable unless its position is changed by rotating the crank. In

my construction, by selecting the point at which the anchor piece is secured to the casement sash at a sufficient distance from the hinge, any danger of the casement being 5 torn from its hinges is overcome.

I claim:

1. A casement operator comprising an anchor piece secured to the casement sash, a hollow tubular arm pivotally mounted 10 upon the casement frame, power actuated means for swinging said arm, said arm having a slot in its one face thereof, a member carried by the anchor piece projecting into said slot and a part pivotally mounted upon 15 said member slidably mounted within said hollow arm.

2. A casement operator comprising a base plate, a casing mounted on said base plate and forming therewith a box like housing, 20 a tubular swinging arm having a part extending beyond its pivotal point and projecting into said housing, power actuated

means within said housing connected to said part for swinging said arm, an anchor piece carried by the casement sash and a part 25 mounted on said anchor piece slidably mounted within said tubular swinging arm.

3. A casement operator comprising a base plate, a casing mounted on said base plate, a swinging arm pivoted on said base plate 30 having a part extending beyond its pivotal point and projecting into said casing, a threaded shaft in said casing, a traveling nut on said shaft connected to said part, an anchor piece secured to the casement sash 35 having a sliding connection with the swinging arm.

In witness whereof I subscribe my signature in the presence of two witnesses.

OSCAR C. RIXSON.
